FORM FOR HOLLOW CONCRETE WALLS

Elmer T. Gabrielson, Yacolt, Wash.

Application October 12, 1951, Serial No. 250,980

3 Claims. (Cl. 25—131)

This invention relates to concrete forms, and more particularly to an improved concrete form assembly especially suited for forming building walls.

The main object of the invention is to provide a novel and improved concrete form assembly for use in molding building walls and the like, said assembly being simple in construction, being easy to erect, and providing improved cast wall features, such as uniform distribution of the aggregate through the wall elements, the provision of vertical, spaced hollow portions in the wall to provide economy in utilization of the concrete and heat insulation, and provision for forming door and window openings.

A further object of the invention is to provide an improved concrete molding form for casting wall elements of buildings, the concrete form assembly involving inexpensive components, being easy to set up, being easy to remove after a wall has been cast, and being durable in construction.

Further objects and advantages of the invention will become apparent from the following description and claims, and from the accompanying drawings, wherein:

Figure 1 is a top view of a typical section of a concrete wall mold constructed in accordance with the present invention.

Figure 2 is a side elevational view of the concrete wall mold section of Figure 1.

Figure 3 is a vertical transverse cross sectional view taken on the line 3—3 of Figure 2.

Figure 4 is a vertical transverse cross sectional view taken on the line 4—4 of Figure 2.

Figure 5 is a vertical transverse cross sectional view taken on the line 5—5 of Figure 2.

Figure 6 is a fragmentary longitudinal vertical cross sectional view taken through the upper portion of a section of concrete wall illustrating the manner in which the form clamps may be removed from the mold assembly at the conclusion of the wall forming operation.

Figure 7 is a perspective view of the carrier bar employed in Figure 6.

Referring to the drawings, the concrete form assembly is designated generally at 11 and comprises the longitudinally extending spaced parallel vertical plates 12, 12 which are secured at their vertical margins to the upstanding arms 13, 14 of respective form clamp assemblies of the type fully described in my copending patent application Serial No. 191,168, filed October 20, 1950, and entitled "Concrete Form Clamps." As is fully described and illustrated in the aforementioned copending patent application, the clamping assembly is supported by vertical stud bars 15, and the plate members 12, 12 are secured to the vertical arms of the clamping assemblies. The clamping assemblies include horizontally extending top bars 17, and horizontally extending intermediate bars 18, 18 which are notched to allow the vertical reinforcing bars 20 to extend upwardly therebetween, said bars 20 passing between the top horizontal bars 17, 17, as shown in Figure 6.

2

The improved concrete form assembly includes bulkhead members 21 disposed wherever it is necessary to terminate the wall being cast, as for example at doorways, window openings and the like. Each bulkhead member 21 comprises a transversely extending top angle bar 22 to the intermediate portion of which is secured a depending plate 23 arranged to fit closely between the longitudinal form wall plate 12, 12 and extending substantially to the bottom plane of the form, as shown in Figure 5. Secured to the outer ends of the top bar 22 are the depending, vertical angle bars 24, 24 arranged to engage the outer surfaces of the form plates 12, 12 and to maintain the bulkhead 21 in its correct transverse position with respect to the main longitudinal form plates 12, 12. Secured to the depending plate 23 at its intermediate portion is the vertical channel strip 25 which is intended to serve as a core for forming a vertical groove in the end of the concrete wall, said vertical groove being provided for the purpose of receiving portions of the window or door framing structure to be mounted in the wall opening being thus formed. The bulkheads 21 are also provided at their ends with vertical fillet elements 26, 26 to provide rounded corners in the concrete wall blocks formed thereby.

Longitudinally disposed between successive form clamp assemblies are a plurality of cavity forming structures 27 adapted to form regularly spaced vertical cavities in the wall to provide heat insulation and to reduce the amount of concrete required to form a wall of given size. Each core structure 27 comprises a first transverse supporting bar 28 formed at its ends with right-angled bearing elements 29, 29 adapted to engage on the top edges of the form wall plates 12, 12, as shown in Figure 4, and a second bracket structure 30 including the respective spaced side bars 31, 31 on the opposite sides of the core structure formed at their top ends with hooks 32 adapted to engage over the transverse top rod 17 of a form clamp assembly, as shown in Figure 3. The bars 31, 31 are connected by transverse arms 33, 34 and secured between the bars 31, 31 below the arm 34 is the longitudinally extending core plate 35. The opposite end of core plate 35 is secured to the intermediate portion of the cross bar 28 and is thus supported on the top edges of the form plates 12, 12.

Secured to the intermediate portions of the arms 33, 34 is the vertical bar element 36 formed at its top portion with the hook 37 adapted to be employed as a handle for raising the core assembly and removing same after the wall has been cast.

The core plate 35 is tapered downwardly so as to facilitate the removal of the plate from the wall at the conclusion of the molding operation. Each core plate 35 is formed with a plurality of vertical slots 39 opening at the bottom edge of the core plate, said slots 39 being evenly spaced and defining vertical depending core elements 40 therebetween. Said core elements 40 are hollow, to lighten the core plate 35 and are vented at their top ends by vertical passages 41 connecting the upper portions of the internal cavities of the vertical core elements with the top edge of the core plate 35.

The purpose of the vent passages 41 is to prevent the formation of a vacuum inside the hollow core element 40 when the core plate is being removed at the completion of the wall casting process, whereby removal of said core plates is facilitated. It will be understood that the bottom ends of the internal cavities of the core elements 40 are closed since the bottom edge of the core plate 35 engages the bottom supporting surface on which the form is mounted.

In forming a wall, the assembly is arranged, as shown for example in Figure 1, with the bulkheads 21 in place and with the core plates 35 arranged between and paral-

lled to the wall plates 12, 12 and supported at their ends in the manner above described. With the form in assembled position, the concrete may be poured, and after the concrete has set, the core plates 35 may be removed by lifting them out of the form, employing the handles 37 as described above. The form clamps may then be removed in any suitable manner, as for example in the manner described in the above identified copending application, or by the use of a carrier bar shown in Figures 6 and 7. The carrier bar, designated at 42, comprises an elongated handle 43 having the opposing yoke bars 44, 44 secured to an end thereof, said yoke bar being connected by a transverse pin on which is pivotally mounted the depending hook element 45. Pivoted to the ends of the bars 44, 44 are the link bars 46, 46, and pivoted between the ends of the link bars 46, 46 is the hook member 47 which faces laterally, as shown in Figure 7. The hook member 47 is provided opposite its hook portion 48 with the handle portion 49. In using the carrier bar 42, the lower hook member 45 is engaged with one of the transverse top bars 17 of the form clamp and the hook element 48 is engaged around the upstanding reinforcing bar 20 in the manner shown in Figure 6. The axis of the opening in the hook element 48 is inclined at an acute angle with respect to the axis of the hook member 47, whereby the hook element 48 may exert a frictional clamping action on the reinforcing bar 20 when the member 47 is rotated upwardly. The operator therefore holds the handle 43 with one hand and the handle 49 with the other hand, exerting upward force on the handle 49 to clamp the hook member 47 to the rod 20, and then exerts upward force on the handle 43, whereby an upward pull is transmitted to the form clamp assembly through the hook member 45, lifting the form clamp assembly and thereby facilitating its removal from the form. The form clamp assembly may, of course, be disengaged from the form by other means such as described in the aforementioned copending patent application, the details of said means for disengaging the form clamp forming no part of the present invention.

While a specific embodiment of an improved concrete form assembly has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a concrete form, a pair of spaced parallel vertical plates, brace means connected to the plates and arranged to support said plates in vertical parallel position, respective transverse bulkhead members disposed between said plates, each bulkhead member comprising a transverse top bar slidably engaging and being horizontally movable on the top edges of said plates, a depending rectangular bulkhead plate secured to said top bar and fitting transversely between said first named plates, respective vertical depending guide bars of substantial length secured to the

ends of said top bar and slidably engaging the outer surfaces of said first named plates, a vertical core plate disposed centrally between said first named plates and being arranged parallel thereto, a first transverse support member secured to the top edge of said core plate at one end thereof and engaging the top edges of said first named plates, a transverse bar at the top end of said brace means, and hook means at the top edge of the core plate at the other end thereof engaging said transverse bar, said hook means comprising upwardly projecting, spaced hook elements secured to and located outwardly adjacent the opposite sides of said core plate.

2. In a concrete form, a pair of spaced parallel vertical plates, a clamp assembly engaging the opposite outer sides of said parallel vertical plates, a transverse bar at the top end of said clamps assembly, a vertical core plate, disposed centrally between said first named plates and being arranged parallel thereto, a first transverse support member secured to the top edge of said core plate at one end thereof and engaging the top edges of said first named plates, and hook means at the top edge of the core plate at the other end thereof engaging said transverse bar, said hook means comprising upwardly projecting, spaced hook elements secured to and located outwardly adjacent the opposite sides of said core plate.

3. In a concrete form, a pair of spaced parallel vertical plates, respective transverse bulkhead members disposed between said plates, each bulkhead member comprising a transverse top bar slidably engaging and being longitudinally movable on the top edges of said plates, a rectangular depending bulkhead plate secured to said top bar and fitting transversely between said first named plates, and respective vertical depending guide bars of substantial length secured to the ends of said top bar, said hook means comprising upwardly projecting, spaced hook elements secured to and located outwardly adjacent the opposite sides of said core plate, and slidably engaging the outer surfaces of said first named plates, a vertical core plate disposed centrally between said first named plates and being arranged parallel thereto, a first transverse support member secured to the top edge of said core plate at one end thereof and engaging the top edges of said first named plates, a clamp assembly engaging the opposite outer sides of said parallel vertical plates, a transverse bar at the top end of said clamp assembly, and hook means at the top edge of the core plate at the other end thereof engaging said transverse bar, said core plate being formed with a plurality of vertical slots opening at the bottom edge of said core plate and defining depending arms therebetween, said arms being hollow, the top walls of said arms being formed with relatively small vertical passages to allow air to enter the arms when the core plate is removed.
